United States Patent Office.

WILLIAM S. SIMPSON, OF BEREAL, OHIO.

Letters Patent No. 77,548, dated May 5, 1868.

IMPROVED MOP-WRINGER AND BRUSH.

The Schedule referred to in these Letters Patent and making part of the same.

TO ALL WHOM IT MAY CONCERN:

Be it known that I, WILLIAM S. SIMPSON, of Berea, in the county of Cuyahoga, and State of Ohio, have invented a new and improved Combined Mop and Scrub-Brush; and I do hereby declare that the following is a full, clear, and exact description thereof, which will enable those skilled in the art to make and use the same, reference being had to the accompanying drawings, forming part of this specification.

This invention relates to improvements in utensils used for cleaning floors of dwellings, stairs, and steps, or walls, and for all similar purposes; and it consists in combining, with the scrub-brush, rollers, between which a mop or absorbing-cloth is confined and operated, as hereinafter described.

Figure 1 represents a longitudinal side view of the machine, showing the brush and the rollers, and its general construction.

Figure 2 is a longitudinal edge view, showing more distinctly the frame and levers to which the brush and the rollers are secured.

Figure 3 is a section through the line *x* of fig. 1.

Similar letters of reference indicate corresponding parts.

A represents the frame, to the lower portion of which the brush is secured by clevis-fastenings and pins, as seen at *b*.

B is the brush.

C is the handle, which is secured to the upper portion of the frame in any substantial manner.

D is a roller, which is revolved within the frame A, with a pivot at each end, which passes through the frame, as seen at *e*.

F is the upper roller, which is attached by pivots at each end to bent levers, *f*, the form of which is more plainly seen in fig. 2.

These levers are attached to the sides of the frame A by pins, *g*, which pins form the fulcrum of the levers. The outer ends are also attached to the frame A by bolts, *h*, which serve, by screwing up, to bring the rollers nearer together, or to compress the cloth between them, according to the pressure thus imparted.

For the purpose of giving these bent levers a certain degree of elasticity, so as to allow solid particles of matter or slight obstructions to pass between the rollers, there are small spiral springs, *i*, secured around the bolts, as seen in fig. 2.

The mop or absorbing-cloth is marked J, and it is secured between the rollers, as seen in the drawing.

When using the brush B, the ends of this cloth are secured to hooks on the handle, as seen at *m*.

When mopping, the cloth is drawn back and forth, between the rollers, over a pail for squeezing the water therefrom.

n indicates flanges on the levers to prevent the cloth from catching over the ends of the roller.

The brush, B, may be easily detached and used separately, if desired.

The rollers are made of wood, or any other suitable material. The frame and levers are made of malleable iron, or brass, or other suitable metal, and of sufficient size and strength for the purpose intended.

Having thus described my invention, I claim as new, and desire to secure by Letters Patent—

The combination of the frame A, having arms *g*, brush B, rollers D F, levers *f*, adjustable spring-bolt *h* *i*, and mop-cloth J, all constructed and arranged as described, for the purpose specified.

WM. S. SIMPSON.
